F. Walther,
By
James G. Shuey, ATTORNEYS.

UNITED STATES PATENT OFFICE.

FREDERICK WALTHER, OF OMAHA, NEBRASKA.

CRATE.

Application filed May 7, 1926. Serial No. 107,438.

My present invention pertains to metallic, collapsible crates, boxes or the like and it contemplates the provision of a simple and inexpensive device that is adapted to be 5 easily and readily assembled for shipment of merchandise or the like and is also adapted to be knocked-down whereby the person receiving the goods may return the device to the shipper with a slight cost due to the 10 small amount of space that the device will require for knocked-down shipment.

The invention further contemplates the provision of a simple and inexpensive knocked-down box that is adapted for repeated 15 shipments and requires but small amount of storage space when knocked-down.

The invention in all of its details will be fully understood from the following description and claims when the same are read 20 in connection with the drawings accompanying and forming part of this invention, in which—

Figure 1 is a perspective view of the completely assembled device.

Figure 2 is a central vertical longitudinal section of the device.

Fig. 3 is a top plan view of the device showing portions of the same broken away and in horizontal section.

Figure 4 is a detail vertical sectional view taken in a plane indicated by the line 4—4 in Figure 1.

Fig. 5 is a diagrammatical view showing box in collapsed position.

Figure 6 is a view showing several of the boxes stacked.

Before entering into a detailed description of my invention, I would have it understood that although my device is adapted for 40 shipment the primary object is for local delivery such as for store use where the driver of a delivery wagon after each delivery to a customer may collapse a box for future use.

Similar numerals of reference designate corresponding parts in all of the views of the drawings.

My novel device comprises the end walls 7 that are flanged at 8 as illustrated. The 50 flanged portions 8 are provided with the knuckles 9 and at their lower ends the sides or ends 7 are provided with the upwardly bent edges 10 as clearly shown in Figure 2. These bent portions 10 are also provided 55 with knuckles 11 and at 12 on the upper edges

of the ends 7 I provide the downwardly bent edges.

Arranged in the end walls 7 are hand holes 13 provided with the interior flanges 14 and an exterior flange 15 for reenforcing 60 purposes.

The box further comprises the side sections 16 having the outer knuckles or hinges 17 and at 18 I illustrate the pintles of the knuckles 9 and 17 through the medium of 65 which the side walls or sections 16 are hinged with respect to the end walls 7. The side sections 16 are further provided with the bent ends 19 and the said side sections of each side of the box comprise two members 70 that are hinged at 20. These side sections are hinged in the center as well as at their ends so that the side sections of each side 16 will collapse inwardly so that the members of one side section when the box is collapsed 75 fall upon and rest against the members of the opposing side section as clearly shown in Figure 5.

Hinged at 22 so as to move up against the sides or ends 7 are the bottom sections 80 21. Passing through the hinges 22 are the pintles 23 and these pintles also pass through the knuckles, or hinges 11 of the ends 7 whereby these elements are hinged with respect to each other.

Each of the bottom sections 21 are provided with the extensions which are downwardly bent and indicated by 24 while the side walls 16 are provided with the slots 25 of such a construction that on movement 90 of the bottom sections 21 downwardly the prongs 24 will ride into and be securely held by the side sections 16. However, as shown in Figure 4 I provide the integral flanges 26 that act after the manner of rests or 95 supports for the bottom walls. Further I provide the bottom walls 21 with the bent edges 23. By reference to Figure 5 it will be seen that when set up the boxes are slightly larger at their lower ends than at 100 their upper ends, so that in stacking they will form a support one for the other.

In the practical use of the invention, when it is desired to set the box up from the collapsed position shown in Figure 5 it is 105 merely necessary to pull the ends 7 away from each other to the limit of movement. The center hinges of the side sections will only allow said hinges to move to a point 110 where the members of each side section are

in parallel relations with respect to each other and prevent the side sections from canting outwardly. The bottom sections first one then the other are dropped so that 5 the prongs enter the slots of the side walls and assume their proper position and in this connection I would have it understood that the bottom sections when in set up position are so constructed that one of the 10 bottom sections slightly laps the other. It will be seen that the setting up of the box is extremely simple. Collapsing of the box merely requires pulling up of the bottom sections so that they rest against the end 15 sections and then pushing the end sections toward each other which action will cause the side sections 16 to fold one against the other.

I wish it distinctly understood that this 20 box may be cut out, giving the effects of ribs or slats and not in solid pieces as shown in the drawings, thereby making it available as a poultry crate etc.

What I claim, is—

- 25 1. A collapsible box comprising end walls, side walls comprising two members, centrally hinged to each other and to the end walls, said side members having slots therein, flanges formed in the side members adjacent the slots, bottoms hinged to the end walls, and integral prongs formed in the bottoms and adapted to seat in the slots of the side walls and rest on the integral flanges thereon.
- 30 2. A knock down box comprising end walls having handles therein, knuckles formed on the side portions of the end walls and also formed on the lower portion of the end walls, bottom walls having knuckles formed thereon, pintles for securing the bottom walls in hinged relation to the knuckles

on the lower end of the end walls, side walls comprising two sections hinged with respect to each other so that hinged movement is inwardly, knuckles formed on the sections of 45 the side walls and adapted to seat in the knuckles on the side edges of the end walls, pintles passing through the said knuckles for hinging the sections of the side walls with respect to the end walls; said side walls 50 having apertures therein and integral supports formed adjacent the slots on the interior surface of the side sections and means formed on the bottom walls for engaging the slots and resting on the supports; said 55 bottom sections being overlapped at their edges.

3. A collapsible crate having end walls, centrally hinged side walls pivotally connected with the end walls; said side walls 60 having slots therein and flanges formed in the side walls, bottom walls hinged to the end walls and prongs adapted to seat in the slots of the side walls.

4. A crate comprising end walls having 65 handles therein, knuckles formed on the walls, bottom walls having knuckles formed thereon, pintles adapted to secure the end and bottom walls to each other in hinged manner, side walls comprising two sections 70 hinged to each other and having means adapted to hinge the side walls with respect to the end walls, apertures formed in the side walls and supports adjacent the apertures and means formed on the bottom walls 75 for engaging the apertures and resting on the supports; said bottom walls having their free ends overlapped with respect to each other.

In testimony whereof I have hereunto 80 set my hand.

FREDERICK WALther.
